GRADING TRAY

Robert H. Murray, 2412 Lancaster Court,
Falls Church, Va. 22043

Filed Oct. 18, 1968, Ser. No. 14,065

Term of patent 14 years

Int. Cl. D19—08

U.S. Cl. D25—1

FIGURE 1 is a top plan view of a grading tray showing my new design;

FIGURE 2 is a right side elevational view thereof;

FIGURE 3 is a bottom plan view thereof;

FIGURE 4 is a top plan view thereof.

The side opposite to the side shown in FIGURE 2 is identical thereto. The back is non-configured and has an outline identical with the outline of FIGURE 1.

I claim:

The ornamental design for a grading tray, as shown and described.
